(57) **CLAIM**

The ornamental design of a wireless headset, as shown and described.

DESCRIPTION

FIG. 1 is a front elevational view of an auricular body and buttons are on an outer arc's surface;

FIG. 2 is a rear elevational view of a receiver, the auricular body and a mouthpiece;

FIG. 3 is a left side elevational view of the receiver, the auricular body, the mouthpiece, an earplug and a curved structure, wherein the earplug connects to a curved structure with holes that gradually expands to connect with the auricular body;

FIG. 4 is a right side elevational view of the receiver, the auricular body the earplug and the curved structure, wherein the earplug connects to a curved structure with holes that gradually expands to connect with the auricular body;

FIG. 5 is a top plan view thereof;

FIG. 6 is a bottom plan view thereof; and,

FIG. 7 is a perspective view of a wireless header showing the new design.
